APPARATUS FOR ASSISTING STEERING

John Lester Barr, Chevy Chase, Md.

Application January 10, 1934, Serial No. 706,119

27 Claims. (Cl. 280—150)

My invention relates to a device for facilitating the operation of steering wheels of vehicles, for instance, in such operations as parking and un-parking vehicles in confined spaces. The device 5 permits the steering wheels to be more readily turned.

It is an object of my invention to provide means for compensating for the lateral, or in other words transverse, displacement of the lift 10 element in parking operations so that there shall be approximately uniform lift as long as the device is in use.

Another object of my invention is to provide a novel type of centering means which tends to 15 center the lift element after lateral movement.

A still further object of the invention is to provide a novel type of centering means which comes into operation at a predetermined point in the longitudinal displacement of the lift element 20 from the vertical position.

Yet other objects of the invention are to provide safety catch means to prevent possible falling of the element in its raised position and to 25 provide control means operable from the driver's seat to control the safety catch.

Yet another object of the invention is to provide a sturdily constructed device, easily and simply made and which has parts that can be readily repaired and replaced.

30 With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly 40 understood, I have shown in the accompanying drawings means for carrying the same into practical effect without limiting the improvements in their useful applications to the particular constructions, which, for the purpose of explanation, have been made the subject of illustration.

In the drawings:—

Fig. 1 is a perspective view of the front axle and steering mechanism of the car with my 50 mechanism in place;

Fig. 2 is a diagrammatic top plan of the front wheels and front axle of the car showing the movement of the axle of the car with respect to the foot of the device after contact with the roadway;

Fig. 3 is a view in longitudinal section taken through the latch control mechanism mounted on the steering wheel;

Fig. 4 is a rear elevation of the lift mechanism in its raised position;

Fig. 5 is a top plan view of the mechanism shown in Fig. 4;

Fig. 6 is a view taken along line 6—6 of Fig. 4 looking in the direction of the arrows;

Fig. 7 is a rear elevation of the lift device in 10 its lowered position, the position of the parts when transversely displaced from the vertical being indicated by dotted lines;

Fig. 8 is a view taken along line 8—8 of Fig. 7;

Fig. 8a is a detail showing the operation of the 15 centering ears upon displacement of the lift element longitudinally beyond a predetermined position;

Fig. 9 is a view taken along line 9—9 of Fig. 8 looking in the direction of the arrows;

Fig. 10 is a view taken along line 10—10 of Fig. 8 looking in the direction of the arrows;

Fig. 11 is a side elevation of the device in its lowered position;

Fig. 12 is a view taken along lines 12—12 of 25 Fig. 4, looking in the direction of the arrows;

Fig. 13 is a diagram showing an alternative form of the invention.

Referring to the drawings I have shown the front axle of an automobile 1 upon which are 30 pivoted front wheels 2. There is shown in the drawings a steering post 3 and a steering wheel 4. I have indicated diagrammatically the mechanism which is designated generally by numeral 5 to steer the front wheels.

Mounted on the front axle in a position which may be to either side of the center of the front axle 1 or approximately at the center as desired is my lift device which comprises a compression element 6 in which is screwed a male member 7 40 provided with a ball 8 at its end which fits within a socket 9 shown in the conically shaped foot element 10. A holding plate 11 holds the ball in the socket formed in the foot 10. A lock nut 13 is adapted to hold compression element 6 and the male member 7 in fixed relationship after adjustment is made to give a satisfactory length to the lift mechanism for the particular car to which the mechanism is adjusted.

At the top of compression element 6 is attached 50 a bifurcated stirrup member 14 which may be affixed by a pin 15 to the top of the member 6. Shoulder 16 and the pin 15 hold the member firmly in place.

Through the bifurcated arms 17 of the stirrup 55

member 14 passes a pivot pin 18 on which is pivoted a support 19 which may be keyed to the pivot 18 by means of keys 21. Support 19 is formed with bifurcated arms 22 which have slots 23 or links 23 in their ends. The slot or link structures 23 fit over a pivot member 24. The pivot member 24 is provided with a collar 25 and an extension 26. The extension 26 is provided with an outermost portion of reduced diameter 27 over which fits a holding plate 28 provided with support arms 29. There is a screw member 31 which holds the plate 28 in place. The flange portion 25 prevents movement of the pivot 24 into the slot 23 but permits the arm 22 to slide over the pivot 24. Pivot 24 is provided with a screw threaded recess 32 in its other end. There is a holding washer 33 against which lies a plate 34 similar to plate 28 provided also with support arms 35 corresponding to support arms 29. There is a screw 36 which holds the ensemble together and fits within screw threaded aperture 32 in the pivot 24. As will be seen from Fig. 8, pivot member 24 can slide in the slot or link portions 23 of the arms 22 but will not slip through the links 23 laterally. The pivot 24 is held firmly in place within a cam plate 37 by means of a pin 38.

There is provided a pivot 39 which is affixed by means of a holding pin 41 to the member 19. This pivot 39 carries a roller 42 which is adapted to lie against the lower surface of the cam plate 37.

Pivoted on the pivot 18 are centering ears 44 each of which is provided with a spring engaging member 45. Springs 46 each have one end engaging the supports 29 on the member 28 and spring engaging member 45 on the ear 44 on one side and on the other side there are two corresponding springs 46 which engage at their lower end spring engaging member 45 on the pivoted centering ear 44 and at the upper ends the springs engage supports 35 corresponding to the supports 29. These springs serve a dual function. They tend to hold the support 19 in the position shown in Fig. 10 when the lift element is in its lowered position by reason of the force they exert which causes the roller 42 to seek the position in the center of a cam surface 47 formed on the bottom of the cam member 37. The other function which the springs 46 perform is to hold the pivoted centering ears 44 in the position shown in Fig. 8. Should the compression element 6 swing to such an extreme position in its front or back motion as to permit surfaces 48 on the stirrup shaped member 14 to engage the ends 49 of the centering ears 44, then the springs which control the particular centering ear 44 by exerting a pressure thereon, tend to bring compression element 6 back more nearly into the vertical position.

It is to be noted that the springs thus continually tend to center the device from transverse displacement and, as a separate function, tend to center the compression element into a more nearly vertical position when it is longitudinally displaced beyond a certain angular position.

The practical effect of this latter action is to bring an initial pressure to bear on the foot or ground-engaging member, in addition to the pressure due to its own weight, whereby it more effectively grips the road-bed when brought into action. This minimizes slippage of the ground engaging foot when the car is driven in such a direction as to be lifted by the lift device.

It is to be noted from Fig. 7 that the cam surface 47 is so related to the normal length of the compression element that when the compression

element is laterally displaced, as indicated by dotted lines, yet the lift which will be given to that portion of the vehicle to which the device is attached will be substantially constant. This is of considerable importance since often the compression element 6 and the members 14 and 19 are transversely displaced from that position in which they are when the foot 10, during the use of this device, comes into engagement with the roadway, and when the vehicle is either backed or moved forward to raise that portion of the vehicle upon which the device is carried, the device, unless constructed to provide for this, would not be sufficient for the purpose intended.

The desirability of this provision will become apparent by reference to the diagram shown in Figure 2. It is assumed that the vehicle has been backed in the direction indicated by the arrow, the wheels 2 being cramped to an extreme position in relation to the axle 1, as shown, as the necessities of parking conditions sometimes require. Due to the action of the lateral centering means which the present invention incorporates, the foot 10 occupies a position directly in front of the axle, that is, the axis of the compression element 25 is at an angle of 90° with the axis of the front axle, and passes through the upper pivot *p* of the compression element, as shown. Assume now that it is desired to release part of the weight on the front wheels by means of the lift device, so that the wheels may be readily turned. The car is driven forward to the position shown in dot-dash lines, until the greatest vertical lift is achieved.

In this new position of the car, the center of the foot 10 (which last has remained in its original position with reference to the ground) occupies a point substantially in a vertical plane extending parallel to the axis of the front axle and passing through the upper pivoting point *p* of the compression element. During the action of lifting the car, the pivoting point *p* of the compression element has, however, been displaced laterally through a distance *D* from its original position in relation to the foot 10 which has remained stationary. If the compression element 6 were pivoted at its upper end for simple universal swinging movement, the loss of height following from this lateral displacement would nullify the gain of height due to the intended motion of the pivoting point *p* of the compression element toward a position over the foot 10.

Due to the compensating action of the cam surface 47 and cooperating parts forming part of the present invention, however, the loss of height due to lateral displacement is cancelled, and the identical lift that would be had by driving forward to a point where the center of foot 10 is directly under the pivoting point *p* is secured. This compensating action may be readily visualized by assuming that the axle 1, in Fig. 7, is moved to the left or right along its axis so that the compression element is successively at the three angles of inclination shown. It is apparent that the axle remains at the same height in the three cases. It may be remarked that the displacement distance *D* on either side of the longitudinal axis of the vehicle is with any given vehicle a maximum for a given length of compression element and a given maximum angle of cramp of the front wheels. The span of the cam surface 47 is made sufficiently great so that the compensation above described takes place over this entire range of displacement.

The purpose of the lift is to enable either one or both steering wheels to have the weight upon

them relieved sufficiently to permit the steering wheels to be turned without undue effort on the part of the operator.

By reason of the cam surface 47 the compression element can be laterally or transversely displaced a considerable distance from that in which it is at the time the foot 10, in each operation of this device, first contacts the roadway, and yet the forward or backward movement of the car will give a substantially constant lift within certain limitations of construction. This feature greatly increases the uniform functioning of the device under various operating conditions.

As is apparent from the drawings the whole device is carried by cam plate 37 which is formed with an extension 51. The extension 51 is provided with sloped top and bottom walls 52, see Fig. 6, which fit within sloped walls 53 of a holding bracket 54. The holding bracket 54 is sturdily constructed with a bracing web 55 and a top plate 56. U-bolts 57 pass over the front axle 1 and through the top plate 56 and hold the support 54 firmly in position. The support 54 and extension 51 of the cam plate 37 are bolted together by means of bolts 58.

In operation the device is lowered and is so adjusted that in driving the car either backward or forward over the device, sufficient lift will be given to enable the steering wheels to be readily turned.

In order to raise the compression element 6 I have provided a holding ring 60 to which is firmly attached as indicated at 61, a Bowden wire 62. The Bowden wire 62 is adapted to pass upward and through apertured holding nuts 63 which hold the sheath 64 for the Bowden wire. The apertured holding nuts clamp through a support member 65. Details of the construction are not shown as such are well known in the art. Support 65 is bolted by means of a U-bolt 66 provided with nuts 67 to the front axle 1 of the car, see Fig. 12.

The Bowden wire passes through its sheath 64 to a ring 68 which can be lowered as shown in Fig. 1 or raised and passed over a holding hook 69 as indicated in Fig. 1. When the ring 68 is in its lowered position as shown in Fig. 1 the compression element can be lowered as shown in Fig. 1. When the ring is moved to raised position over holding hook 69 compression element 6 is raised sideways and upward as indicated in Fig. 4, which it occupies behind the front axle. It is to be noted that very little of the clearance of the front axle is lost when the device is in raised position as indicated in Fig. 4, and it is readily apparent that, given a suitably constructed vehicle, the entire device could be so constructed as to leave 100 per cent clearance of the roadway.

In order to provide a safety catch means which will prevent the compression element from falling into lowered position upon failure of the operating mechanism just described, I have provided a U-shaped latch member 70 which is pivoted at 71 on a support 72 formed on support 65. This U-shaped latch member is provided with operating arm 73 to which is attached at 74 a Bowden wire construction 75 which passes through perforated clamping nut 76 attached to the support 65. A tension spring 73' holds the latch 70 in locking position. The clamping nut 76 supports in the customary manner sheath 77 for the Bowden wire. The sheath 77 is fastened by means of a nut 78 to a cylinder head construction 79 held by means of a strap 80 to the

steering post 3. The cylinder head 79 is provided with a central aperture through which passes Bowden wire 75. The Bowden wire 75 then passes through a piston head 81 which may be formed through the piston 82 where it is firmly attached to the piston construction by means of a screw 83. The screw 83 holds a head 84 which carries a ring 85. The piston head 81 slides in a cylinder 86 which is screw threaded at 87 to cylinder head 79. Cylinder 86 is provided with a head which may be integrally formed which head I have indicated at 88. The construction is such that the ring 85 can be pulled by the hand of the operator of the car, the pull on the Bowden wire 75 which pulls downwardly on arm 73, removing the U-shaped latch from its obstructing position directly under element 6. There is a spring 90 which bears against cylinder head 88 and piston head 81 and which urges the parts in the position shown in Fig. 3. It is against the tension of this spring 90 that the Bowden wire 75 is operated to remove U-shaped latch 70 into the position shown in dotted lines in Fig. 12, which will permit the compression element 6 to fall. This latch means, just described, should be operated to release the compression element 6 when it is desired to operate the lift mechanism.

When the ring 85 is released, spring 90 will bring the parts back into the position shown in full lines in Fig. 12 and when the compression element 6 is raised by reason of contact with sloped surfaces 91 on the U-shaped latch 70, this latch will be moved to the side and permit the compression element 6 to pass into the position indicated in Fig. 12. The latch 70 will be displaced laterally as indicated by dotted lines to permit this operation to occur.

In order to provide anti-rattle mechanism I have shown the support 65 extended into bifurcated spring arms 92, see Fig. 11, and Fig. 4, which normally bear against the upper surface of the foot piece 10 and hold the parts in anti-rattle position. The spring arms 92 will give against the tension of the Bowden wire 62 so that when the ring 68 is passed over the catch 69 the parts will be held firmly and resiliently so as to prevent undue motion and noise during travel of the car.

In operation, the ring 68 (Fig. 1) of the latch releasing mechanism is retracted, drawing the latch 70 into the open position shown in dot-dash lines in Fig. 12. The ring 68 of the compression element elevating and lowering mechanism is now removed from the hook 69 and the foot is lowered to the roadway. As the car is moved forwardly or backwardly, the compression element 6 through stirrup member 14 pivots on the axis 18, and as the angle formed with axle 1 is decreased in this operation, frictional engagement of the foot with the roadway operates to pull the compression element into a more nearly central position in back of pin 24. This action proceeds very rapidly, especially so after roller 42 has passed point 94 on the cam face when the lateral centering mechanism operates, and as a result the compression element is quickly centered laterally. Before the compression element 6 and stirrup 14 have hinged sufficiently fore or aft, (depending upon front or back movement of the vehicle) to allow lateral centering to become complete, there is engagement of surface 48 by the end 49 of one of the centering levers 44 as shown in Fig. 8, compression element 6 being put under a definite "gripping" pressure as it

assumes a position of use for lifting. It will be noted that the fact that the compression element is not engaged by these levers 44 until it has moved a substantial distance forwardly or backwardly of the central position facilitates the initial longitudinal bending and lateral centering action.

In Fig. 13 is shown an alternative form of the invention, wherein the working face 103 of the cam 137 in the sector extending from point 104 to point 105, is so shaped that the distance from it to pin 124 (which in the form of the invention already described is constant, this segment being an arc of a circle having its center at 124) in this case gradually increases, as shown. The roller 142, being forcibly pressed against this surface 103 by the action of the tensioning springs 146, causes a downwardly directed force to act on the compression element and associated parts, thus forcing the compression element from its elevated position to a position where the foot is in contact with the roadway, when the lifting ring 63 is released from the hook 69. After the foot has reached the ground and the vehicle has been moved, the roller or cam followers 142 will have entered upon the cam surface 147, and an inwardly directed centering force will act on the compression element. A substantial pressure is thus brought upon the foot 10, insuring a fore or aft gripping action on the pavement in addition to the gripping action secured by reason of its own weight and the weight of associated parts, as well as that produced by the operation of the lateral centering mechanism.

The compression element may, when approximately centered, carry out its lifting function in the normal way, as described heretofore. To draw it into inoperative position the ring 63, Fig. 1, is pulled toward the hook 69, the ring being secured over the hooked catch 69. This is preferably done while the car is in motion, to facilitate disengagement of the foot 10 from the roadway. During the operation of lifting the compression element the leg 6 engages the inclined surface 31 of the latch 78, pushing the latter aside to allow passage of the leg, the latch then swinging back into locking or obstructing position.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. In a device of the character described for a vehicle, a lift element supported by the vehicle and adapted to have both a longitudinal and a transverse movement, and means cooperating with said element substantially preventing loss in effective length of the element when it shall become transversely displaced in its point of initial contact with the roadway.

2. In a device of the character described for a vehicle, a lift element supported by the vehicle and adapted to have both a longitudinal and a transverse movement, and a cam cooperating with the element to substantially inhibit loss in effective length of the element when it shall become transversely displaced in its initial point of contact with the roadway.

3. In a device of the character described for a

vehicle, a lift element supported by the vehicle and adapted to have both a longitudinal and a transverse movement, a roller carried by the element and a cam with which the roller contacts to substantially inhibit loss in effective length of the element when it shall become transversely displaced in its initial point of contact with the roadway.

4. In a device of the character described for a vehicle, a lift element supported by the vehicle and adapted to have both a longitudinal and a transverse movement, a link carried by the element at its end, a pivot fitting within the link, said link permitting pivoting and also movement of the element toward and away from the pivot, and means substantially preventing loss in effective length of the element when transversely displaced.

5. In a device of the character described for a vehicle, a lift element supported by the vehicle and adapted to have both a longitudinal and a transverse movement, a link carried by the element at its end, a pivot fitting within the link, said link permitting pivoting and also movement of the element toward and away from the pivot, and a cam operating with the element to substantially inhibit loss in effective length of the element when it shall become transversely displaced at its initial point of contact with the roadway.

6. In a device of the character described for a vehicle, a lift element supported by the vehicle and adapted to have both a longitudinal and a transverse movement, a link carried by the element at its end, a pivot fitting within the link, said link permitting pivoting and also movement of the element toward and away from the pivot, a roller carried by the element and a cam cooperating with the roller to substantially inhibit loss in effective length of the element when it shall become transversely displaced at its initial point of contact with the roadway.

7. In a device of the character described for a vehicle, a lift element supported by the vehicle and adapted to have both a longitudinal and a transverse movement, a roller carried by the element, a cam cooperating with the element substantially preventing loss in effective length of the element when transversely displaced and spring means tensioning the roller against the cam and tending to overcome the transverse displacement.

8. In a device of the character described for a vehicle, a lift element supported by the vehicle and adapted to have both a longitudinal and a transverse movement, a link carried by the element, a pivot fitting within the link, a roller carried by the element, a cam with which the roller contacts to substantially prevent loss in effective length of the elements when transversely displaced and spring means tensioning the roller against the cam and tending to overcome transverse displacement of the element.

9. In a device of the character described for a vehicle, a lift element movably supported on the vehicle, Bowden wire means to raise and lower the element, latching means to hold the element in its raised position, a second Bowden wire to operate the latching means so mounted as to allow play without binding, and spring means tending to move the wire into latching position, said Bowden wires being operatively unconnected.

10. In a device of the character described for a vehicle, a lift element movably supported on the vehicle, latching means having a supporting

- loop fitting under the element to hold the element in its raised position, a Bowden wire to operate the latching means so mounted as to allow play without binding, a handle for the wire, a plunger, a cylinder in which the plunger moves and means to hold the plunger in spring pressed relation so that the wire shall be in latching position.
11. In a device of the character described for a vehicle, a lift element movably supported on the vehicle, Bowden wire means to raise and lower the element, latching means to hold the element in raised position, a second Bowden wire to operate the latching means so mounted as to allow play without binding, a handle for the wire, a plunger having a head thereon, a cylinder in which the plunger moves and a helical spring surrounding the plunger and bearing against the plunger head to tension the latching means in locked position, said Bowden wires being operatively unconnected.
12. In a device of the character described for a vehicle, an elongated lift element pivoted on the vehicle, a U-shaped latch fitting under the element adapted to engage the element and hold it in its raised position, and means to pivot the latch to release the element, and separate flexible means to raise and lower the compression element, said two means being operatively unconnected.
13. In a device of the character described for a vehicle, an elongated lift element pivoted on the vehicle, a U-shaped latch fitting under the element adapted to engage the element and hold it in raised position, means operable from the driver's seat to pivot the latch to release the element, and flexible means operative from the driver's seat to raise and lower the compression element, said two means being operatively unconnected.
14. In a device of the character described for a vehicle, a lift element, a U-shaped latch fitting under the element adapted to engage the element and hold it in its raised position, a Bowden wire to pivot the latch, means to operate the Bowden wire from the driver's seat, spring means tending to move the wire into its latching position, and other Bowden wire means to raise and lower the compression element, said Bowden wires being operatively unconnected.
15. In a device of the character described for a vehicle, a lift element pivoted on the vehicle, cross-pivoted centering ears and spring means to bring each of the ears into operation only upon displacement from the vertical of the lift element beyond a certain determined position.
16. In a device of the character described for a vehicle, a lift element movably supported on the vehicle and adapted to have both longitudinal and transverse movement on its support means substantially preventing loss in effective length of the element when transversely displaced, and means tending to bring the element back toward the vertical when it has been displaced longitudinally beyond a defined position in either direction.
17. In a device of the character described for a vehicle, a lift element supported by the vehicle and adapted to have both a longitudinal and transverse movement, means substantially preventing loss in effective length of the element when transversely displaced, and means tending to bring the element back toward the vertical when displaced transversely.
18. In a device of the character described for a vehicle, a lift element supported by the vehicle and adapted to have both a longitudinal and transverse movement, means substantially preventing loss in effective length of the element when transversely displaced, and means tending to bring the element back toward the vertical when it has been displaced longitudinally beyond a defined position.
19. In a device of the character described for a vehicle, a lift element supported by the vehicle and upon which the vehicle is adapted to be raised by movement of the vehicle itself in either a backward or forward direction and means to raise the lift element into an inoperative position with its longitudinal axis substantially at right angles to the longitudinal axis of the vehicle.
20. In a device of the character described for a vehicle, a lift element supported by the vehicle and upon which the vehicle is adapted to be raised by movement of the vehicle itself in either a backward or forward direction and means to raise the lift element into inoperative position substantially paralleling the front axle of the vehicle.
21. In a device of the character described for a vehicle, a lift element supported by the vehicle and upon which the vehicle is adapted to be raised by movement of the vehicle itself, means permitting pivoting of the lift element in two planes, and means to raise the lift element into inoperative position substantially paralleling the front axle of the vehicle.
22. In a device of the character described, a lifting element mounted on a vehicle and pivoted for movement laterally to the longitudinal axis of the vehicle, and a cam cooperating with said element to increase the radial length of said lifting element when displaced laterally away from its medial position.
23. In a device of the character described, a lifting element mounted on a vehicle and adapted to assume different angles of inclination about axis substantially coincident with and transverse to the longitudinal axis of the vehicle and a cam cooperating with said element to increase the length of said lifting element as its angle of inclination increases, and to decrease the length of said lifting element as its angle of inclination decreases.
24. In a device of the character described, a lifting element mounted on a vehicle for sidewise movement, and a cam cooperating with said element to maintain the effective length of the lifting element when the vehicle at the place of mounting of the device is moved sidewise with respect to a determined place of contact of the device with the roadway.
25. In a device of the character described, a lifting element mounted on a vehicle, a cam on said vehicle, a cam follower on said lifting element, and means to allow sliding movement of said lifting element whereby the length of said lifting element is increased as its angle of inclination increases and is decreased as its angle of inclination decreases.
26. In a device of the character described, a lifting element movably supported on the vehicle, lifting means operative from a distance to lift said element into inoperative position, a catch to prevent lowering of said element, and means operative from a distance independently of said first operative means, to remove said catch to

allow movement of said element into operative position.

27. In a device of the character described for a vehicle, a lift element supported by the vehicle and upon which the vehicle is adapted to be raised by movement of the vehicle substantially

in the direction of the longitudinal axis thereof, and means to raise the lift element into inoperative position substantially at right angles to the longitudinal axis of the vehicle.

JOHN LESTER BARR.
